UNITED STATES PATENT OFFICE.

GEORGE H. WILLARD, OF HOPEDALE, MASSACHUSETTS, ASSIGNOR TO DRAPER CORPORATION, OF HOPEDALE, MASSACHUSETTS, A CORPORATION OF MAINE.

FEELER MECHANISM FOR LOOMS.

Application filed June 10, 1924. Serial No. 718,206.

To all whom it may concern:

Be it known that I, GEORGE H. WILLARD, a citizen of the United States, and a resident of Hopedale, in the county of Worcester and 5 State of Massachusetts, have invented an Improvement in Feeler Mechanisms for Looms, of which the following description, in connection with the accompanying drawings, is a specification, like characters on the 10 drawings representing like parts.

This invention relates to feeler mechanisms for looms and more particularly to the intermittent type of feeler mechanism wherein the feeler is held in an inoperative 15 position for periods of time and is released periodically to the performance of its feeling function during weaving with the same supply of filling in the shuttle.

In feeler mechanisms of the intermittent 20 type it is desirable that the feeler be held retracted, during the period it remains inactive, to a sufficient degree to prevent it from engaging the filling with an appreciable force upon successive detecting beats. 25 If the filling in the shuttle alone is relied upon to move the feeler to the position in which it is held inoperative, the feeler in most cases will not be held entirely out of reach of the filling upon subsequent detecting beats, with the result that the feeler 30 while held inoperative may engage the filling at the completion of a detecting beat with sufficient force to injure or chafe the filling to some degree.

The feeler obviously is moved forwardly further when it engages a full bobbin than when it engages a partly depleted bobbin, and it has been proposed heretofore to provide a latch that is positioned to engage any 40 one of several notches upon the feeler to hold the feeler retracted in the different positions to which it may be moved forwardly by the filling upon a detecting beat, but such latch means does not hold the 45 feeler entirely out of reach of the filling.

One of the features of the present invention, therefore, resides in a detent device for holding the feeler retracted in a non-feeling position, and which is provided with a 50 cam surface or wedge that serves to impart an additional forward movement to the feeler to hold it either entirely out of reach of the filling, or retracted sufficiently to prevent the feeler from engaging the filling 55 with appreciable force.

Other features of the invention and novel combination of parts will be best understood from the following description and the accompanying drawings of good practical forms of the invention. 60

In the drawings:

Fig. 1 is a perspective view of a loom at the feeler side, showing a feeler mechanism containing the present invention;

Fig. 2 is an enlarged perspective view 65 showing the feeler held in its retracted or non-feeling position;

Fig. 3 is a perspective view showing the mechanism of the present invention applied to the side swipe type of feeler; 70

Fig. 4 is a fragmentary perspective view showing the detent of Fig. 2 raised and beginning to move into position to hold the feeler retracted; and

Fig. 5 is a vertical sectional view through 75 the pivotal support for the detent of Fig. 2.

The feeler mechanism of the present invention is herein shown as associated with means for effecting replenishment of filling when that in the shuttle is substantially 80 exhausted on a detecting beat, but the replenishing mechanism is not illustrated because it may be of any usual type and is well known, and the details thereof form no part of the present invention. The feeler 85 shown in Figs. 1 and 2 is of a type in which the forward movement of the feeler is limited to a straight path extending at substantially right angles to the axis of the shuttle, while the feeler shown in Fig. 3 is 90 of the inclined type that enters the shuttle at an inclination to the axis thereof and is adapted to slide along the filling carrier lengthwise of the shuttle to call for replenishment of filling when the filling in 95 the shuttle is substantially exhausted.

The loom frame 1 may be of usual construction comprising the side frames 2 and breast beam 3 on which is secured at either side of the loom a bracket 4 having bearings 100 for the usual transverse or rock shaft 5 which is operatively in control of the replenishing mechanism. Secured to the rock shaft 5 and extending upwardly therefrom is the arm 6 to which is pivotally connected 105 at 7 a rearwardly extending arm 8, the rear end portion of which is adapted to be engaged at times with an operating member 9 which may be formed as part of or associated with the cam follower. 110

Pivottally mounted at 10 on the lug 11 rising from the loom frame is the transmitter 12, the end 13 whereof underlies the latch 8. The transmitter 12 has connected thereto the 5 end portion 14, in which is movable the controller 15, in the present instance shown as an arm pivotally mounted at 16 and normally under the influence of a spring 17, tending to move the end of the controller 15 10 rearwardly in the slotted portion 14 of the transmitter. These parts are all of usual and well known construction and operate in a well known manner to effect replenishment of filling when the controller 15 is moved 15 forwardly upon indication of substantial exhaustion of filling, the transmitter 12 at such time being tilted by the controller 15 as the latter passes over the inclined end, or cam, of the end portion 14 of the transmitter. 20 Mounted on the loom frame is a bracket 18 which may be secured adjustably to the frame by means of a bolt 19 passing through a slot 20 in the loom frame, and the feeler stand 21 is adjustably secured to the bracket 25 18 by a bolt 22. The feeler stand 21 is shown as consisting of an upper and a lower plate secured together by screws 23, and between these plates is formed a slide-way for the feeler 24. The feeler 24 may be variously 30 constructed, and as shown, has a forwardly extending stem 25 which is guided in the feeler stand, and the feeler is urged rearwardly to its feeling position by a coiled spring 26 confined within the feeler stand. 35 Pivottally mounted at 27 upon the feeler is the actuator 28, the end portion 29 of which is normally held raised by a spring actuated pin 30, but is adapted to be depressed to engage the controller 15 when the filling is 40 substantially exhausted, as is well understood with this class of feeler mechanism. The actuator 28 has connected thereto the abutment 28^x which, when the filling is substantially exhausted in the shuttle, is 45 adapted to engage the wall of the shuttle, or a part carried by the lay, to depress the end 29 of the actuator into position for engagement with the controller 15 as the lay moves forwardly. 50 The lay is provided with the usual shuttle box which is adapted to receive the shuttle 31, and the front wall 32 of the shuttle box and the wall 33 of the shuttle are slotted as usual to permit the feeler tip 34 to enter the 55 shuttle and feel the filling on a detecting beat. All of the parts so far described may be of any usual or desired character whereby when the filling is substantially exhausted, replenishment may be effected without stopping the loom. 60 As stated, the present invention relates to the feeler mechanism of the intermittent type, and means for holding the feeler 24 in an inoperative position for a period of time and 65 then releasing it, will now be described.

In the construction shown in Figs. 1 and 2, one face of the forwardly extending stem 25 of the feeler is notched to form the shoulder 36, while the end of the stem is provided with the inclined face 37. A detent 38 is provided to engage the shoulder 36 and hold the feeler in its retracted or non-feeling position, and the detent is shown as pivotally supported by a bracket 39 having a rearwardly extending arm 40 that is 70 slidably secured to the feeler stand 21 and may be clamped in different positions of adjustment by a bolt 41 extending through a slot 42. The bracket 39 is provided at one side of the stem 25 with a rearwardly extending sleeve 43 in which a bolt 44 is rotatably mounted, and a reduced portion of this bolt extends through a drill hole in the supporting arm of the detent and is rigidly secured to the arm by tightening the nut 45 75 at the outer end of the bolt to clamp the arm between the nut 45 and the shoulder 46. The arrangement is such that the bolt rotates with the detent.

The outer end of the detent is provided 80 with an inclined face 47 that engages the inclined face 37 of the stem and rides upwardly upon the face 37 as the feeler 24 is pushed forwardly. The outer end of the detent is also provided with the cam face 48 85 adapted to engage the shoulder 36 and hold the feeler retracted. In the construction shown, the detent is rocked downwardly by a coiled spring 49 that surrounds the sleeve 43, and one end of the spring is secured to the bracket 39 at 50 while the other end is secured to the head of the bolt 44 at 51. The arrangement is such that the tension of the 90 spring rotates the bolt in a direction to swing the detent downwardly, and the tension of the spring may be varied by backing off the nut 45 so that the bolt may be turned in one direction or the other in the detent, and then tightening the nut.

The cam face 48 of the detent should be 95 so positioned that it will engage the shoulder 36 of the feeler and hold the feeler retracted when it is pushed forwardly by a substantial amount of filling in the shuttle, but will fail to engage this shoulder when 100 the filling has been unwound to nearly an exhausted condition so that the feeler will be free to feel the condition of the filling upon each detecting beat. To facilitate accurate adjustment of the detent the bracket 39 is provided with an adjusting screw 52 that extends into a threaded hole in the feeler stand and has a reduced portion that rotates in a notch 53 of the bracket. The bracket 39 may be adjusted either in or out 105 by rotating the adjusting screw 52 and may be clamped in the adjusted position by tightening the nut 41.

The construction of the cam face 48 is 110 important because it serves not only to hold 115

the feeler retracted but also to impart a further forward movement to the feeler as the detent moves downwardly, and this is due to the fact that the cam face exerts a 5 wedging or cam action upon the shoulder 36. The tension of the spring 49 may be such that it will overcome the force of the spring 26 and will force the detent downward with camming effect until the detent 10 strikes the lug 54, or the tension of the spring may serve merely to force the cam face quickly into engagement with the shoulder 36 and hold the feeler in the maximum forward position to which it is moved by any 15 detecting beat. Since the feeler 24 when struck by the filling moves forward rapidly, the inclined surface 37 forces the detent 38 upward quickly, and it is desirable to provide a stop to limit the upward movement of the detent so that it will not be thrown too high. To this end the bracket 20 39 is provided with a finger 39* that serves as a stop.

After the feeler has been held inactive for 25 a predetermined number of picks, it is desirable to release the same so that it may again feel the condition of the filling in the shuttle, and if a substantial amount of filling is still present, the feeler will again be 30 pushed forward by the filling far enough to be engaged and held by the detent 38. Various means may be provided for actuating the detent periodically to release the feeler, and in the construction shown this is 35 accomplished by a plunger 55 slidably mounted in the lug 54, and the plunger may be actuated from a going portion of the loom by a wire 56 enclosed within a sheath 57. The opposite end of the sheath is secured to a block 58 mounted upon the loom frame, and the opposite end of the wire 56 is secured to a plunger extending from the block 58 into position to be actuated by the 40 rocking lever 59 pivoted at 60. The lever 59 has a lug 61 that engages a projecting head 62 secured to a spoke of the gear 63, and as the head is forced against the lug by the rotating gear, it actuates the lever 59 to trip the detent 38. The gear 63 is shown as 45 one of a chain of gears, 64, 65 and 66, which actuate the usual take-up roll.

In applying the type of mechanism above described for holding the feeler inactive to the side swipe feeler, it may be desirable to 55 modify the construction somewhat to accommodate the lateral swinging movement of the feeler which occurs when the feeler calls for filling replenishment. A somewhat different construction is therefore shown as applied to the side swipe feeler of Fig. 3. This 60 feeler is of well-known construction and consists of a feeler stand 67 provided with the inclined feeler 68 supported for sliding movement forwardly and in a lateral direction. The feeler is urged to its feeling

position by a spring 69 and the forward portion of the feeler extends slidably through a bearing block 69*. At one side of the feeler stand 67 is mounted a bracket 70 that may be adjusted to different positions by a 70 screw 70* similar to the manner in which the bracket 39 is adjusted. Upon the bracket 70 is pivotally mounted a detent 71 that extends in a forward direction and is mounted upon a pivot pin 72 which may be 75 similar in construction to the pivot pin 44, and is rotated by a coiled spring 73.

The forward portion of the feeler stem is provided with a block 74 rigidly secured thereto by a set screw 75 and the block has a laterally extending arm 76. The detent 71 has an inclined face 77 positioned to be engaged and elevated by the arm 76 as the feeler is pushed forwardly upon a detecting beat. The forward end of the detent 71 80 is provided with a cam face 78 which cooperates with the shoulder or rear face of the arm 76, similar to the cam face 48 above described. The laterally extending arm 76 permits the detent to be spaced from the 85 feeler so that the detent will not interfere with the side swipe movement of the feeler. The detent may be tripped to release the feeler by a plunger slidably mounted within the boss 79, and the plunger engages a lug 80 extending laterally from the detent. The plunger is actuated from a going part 90 of the loom as described in Fig. 1. The upward movement imparted to the detent 71 as the feeler is forced forwardly is limited 95 by engagement of the lug 80 with the bar 81 of the bracket 70.

The mechanism shown in Fig. 3 for holding 100 a feeler in the retracted position may also be used in connection with the type of feeler shown in Figs. 1 and 2 which does not partake of a side swipe movement. The construction of the cam face in both Figs. 2 and 3 is such that the force of gravity helps 105 to move the detent in a direction to cam or wedge the feeler forwardly, and the vibration of the loom will also serve to force the detent in further wedging engagement with the shoulder of the feeler.

In Fig. 3 the side swipe feeler 68 is shown 110 as provided with a tip 82 that is formed of wood, this type of feeler tip being desirable in that it is less likely to injure the filling than the metal or other types of feeler tips heretofore used. The feeler tip 82 may be secured to the feeler by means of a tongue 83 that extends into a slot formed in the end 115 of the feeler and may be fastened in place by a pin 84.

What is claimed is:

1. In a feeler mechanism for looms, the combination of a feeler, a spring normally acting in a direction to move the feeler towards feeling position, a detent having a 120 cam face for holding the feeler in forward 130

or non-feeling position and constructed to urge the feeler frontwardly in the direction of its length, a shoulder upon the feeler positioned to engage said cam face, and a spring 6 acting upon said detent to move the cam face so that successive portions of the cam face move against the active face of the shoulder with a wedging action to impart further frontward movement of the feeler.

10 2. In a feeler mechanism for looms, the combination of a feeler, a spring normally acting in a direction to move the feeler towards feeling position, a detent having a cam face for holding the feeler in frontward 15 or non-feeling position, a shoulder upon the feeler positioned to be engaged by said cam face, and a spring acting upon said detent to move the cam face so that successive portions of the cam face press against the shoulder with a wedging action to move the feeler further frontwardly in the direction of its length.

18 3. In a feeler mechanism for looms, the combination of a feeler, a spring normally 25 acting in a direction to move the feeler towards feeling position, a detent having a cam face for holding the feeler in frontward or non-feeling position, a shoulder upon the feeler positioned to be engaged by said cam face, a spring acting upon said detent to move the cam face so that successive portions of the cam face press against the shoulder with a wedging action to move the feeler further frontwardly in the direction 30 of its length, and means for imparting movement from a power actuated part of the loom to the detent to release the feeler.

4. In a feeler mechanism for looms, the combination of a feeler, a spring normally 40 acting in a direction to move the feeler towards feeling position, a detent mounted for movement to and from its active position and having a cam face for holding the feeler in retracted position, a shoulder upon 45 the feeler positioned to be engaged by the tip of the cam face when the feeler is moved frontwardly on a detecting beat by a substantial amount of filling in the shuttle, and the cam face being constructed so that successive portions thereof press against the shoulder with a wedging action to impart a further frontward movement to the feeler.

5. In a feeler mechanism for looms, the combination of a feeler, a spring normally 55 acting in a direction to move the feeler towards feeling position, a detent mounted for rocking movement downwardly into active position and having a cam face for holding the feeler in retracted position, a shoulder upon the feeler positioned to be engaged by the tip of the cam face when the feeler is pushed frontwardly on a detecting beat by a substantial amount of filling in the shuttle, and the detent being constructed to move downwardly an increasing

amount upon subsequent detecting beats to bring successive portions of the cam faces into wedging action with the shoulder and cause the cam face to hold the feeler in a further frontward position should the feeler 70 engage the filling on a subsequent detecting beat.

6. In a feeler mechanism for looms, the combination of a feeler, a spring normally 75 acting in a direction to move the feeler towards feeling position, a shoulder upon the feeler, a detent positioned to engage the shoulder and hold the feeler in a retracted or non-feeling position when the feeler is pushed frontwardly on a detecting beat by 80 a substantial amount of filling in the shuttle, a wedging surface upon the detent that is urged in a direction to cause successive portions of such surface to press against the shoulder with wedging action to maintain the feeler in a further retracted position should it be urged frontwardly slightly by the filling on a subsequent detecting pick.

7. In a feeler mechanism for looms, the combination of a feeler, a spring normally 90 acting in a direction to move the feeler towards feeling position, a shoulder upon the feeler, a detent movable to and from holding engagement with said shoulder, an inclined surface upon the feeler for moving the detent out of the path of the shoulder so that the detent may snap into holding 95 engagement with the shoulder when the feeler is pushed frontwardly on a detecting beat by a substantial amount of filling in the shuttle, a wedging surface upon the detent, and means for urging the wedging surface in a direction to impart further frontward movement to the feeler.

8. In a feeler mechanism for looms, the combination of a feeler, a spring normally 100 acting in a direction to move the feeler towards feeling position, a shoulder upon the feeler, a detent mounted for rocking movement to and from the shoulder, an inclined surface upon the feeler for moving the detent upwardly out of the path of the shoulder so that the detent may drop back of the shoulder when the feeler is pushed frontwardly on a detecting beat by a substantial amount of filling in the shuttle, a stop for limiting the upward movement of the detent, and a wedging surface upon the detent for moving the feeler further frontward as the detent moves downwardly after 115 engaging the shoulder.

9. In a feeler mechanism for looms, the combination of a feeler slidably supported and having its movement restricted to a 125 single path extending at approximately right angles to the shuttle axis, a spring normally acting in a direction to move the feeler towards feeling position, a notch formed in a side of the feeler to provide 130

10 a shoulder, a detent for holding the feeler in frontward or non-feeling position when the feeler is pushed frontwardly by a substantial amount of filling in the shuttle, a cam face upon the detent, and a spring acting upon said detent to move the cam face in a direction to cause successive portions of the cam face to act upon said shoulder with wedging effect to move the feeler further frontwardly.

10. In a feeler mechanism for looms, the combination of a feeler mounted to enter the shuttle in a direction substantially at right angles to the longitudinal axis of the shuttle, an actuator constructed and arranged to be engaged and operatively positioned by a part on the lay when the filling is substantially exhausted on a detecting beat, a detent for holding the feeler in a retracted position beyond the reach of the filling during its periods of inactivity, and a part connected to the feeler for engagement by the detent, the detent being provided with a curved cam surface that is moved by the detent to cause successive portions of the cam surface to act upon the shoulder with wedging action to move the feeler frontwardly in the direction of its length to an inoperative position.

11. In a feeler mechanism for looms, the combination of a feeler mounted to enter the shuttle in a direction substantially at right angles to the longitudinal axis of the shuttle, an actuator constructed and arranged to be engaged and operatively positioned by a part on the lay when the filling is substantially exhausted on a detecting beat, a detent for holding the feeler in a retracted position beyond the reach of the filling during its periods of inactivity, and a part connected to the feeler for engagement by the detent, the detent being provided with a curved cam surface that is moved by the detent to cause successive portions of the cam surface to act upon the shoulder with wedging action to move the feeler frontwardly in the direction of its length to an inoperative position.

ranged to be engaged and operatively positioned by a part on the lay when the filling is substantially exhausted on a detecting beat, a detent for holding the feeler in a retracted or non-feeling position during its period of inactivity, a laterally projecting shoulder upon the feeler for engagement by the detent, and a cam surface upon the detent supported so that it will exert a wedging action upon the feeler to move the same further forward in the direction of its length as successive portions of the cam surface press against said shoulder. 45 45

12. In a feeler mechanism for looms, the combination of a feeler, a spring normally acting in a direction to move the feeler toward feeling position, a detent having a relatively long inclined cam face for holding the feeler in frontward or non-feeling position, a shoulder upon the feeler positioned to be engaged by said cam face, and the cam face being supported by the detent to move automatically into wedging engagement with said shoulder when the feeler is pushed frontwardly by a substantial amount of filling and adapted to impart a further frontward movement to the feeler in the direction of its length as successive portions of the cam surface press against said shoulder with wedging action. 50 55 60 65

In testimony whereof, I have signed my name to this specification.

GEORGE H. WILLARD.
